corporation of California

Application March 23, 1953, Serial No. 24,175

Term of patent 14 years

(Cl. D52—1)

To all whom it may concern:

Be it known that we, Frank T. Walsh, a citizen of the United States of America, resident of Pasadena, in the county of Los Angeles, State of California, and Roy T. Heath, a citizen of the United States of America, resident of Temple City, in the county of Los Angeles, State of California, have invented a new, original, and ornamental Design for a Galvanometer, of which the following is a specification, reference being had to the accompanying drawing, forming a part thereof.

In the drawing,

Fig. 1 is a rear elevation of a galvanometer, showing our new design;

Fig. 2 is a plan view of the galvanometer;

Fig. 3 is a front elevation of the galvanometer;

Fig. 4 is a left side elevation of the galvanometer; and

Fig. 5 is a right side elevation of the galvanometer.

We claim:

The ornamental design for a galvanometer, as shown.

FRANK T. WALSH.
ROY T. HEATH.
